(57) **CLAIM**

The ornamental design for an electronic device, as shown and described.

DESCRIPTION

FIG. 1 is a perspective view of an electronic device showing the new design;

FIG. 2 is a front elevation view of the electronic device of FIG. 1;

FIG. 3 is a rear elevation view of the electronic device of FIG. 1;

FIG. 4 is a left-side elevation view of the electronic device of FIG. 1;

FIG. 5 is a right-side elevation view of the electronic device of FIG. 1;

FIG. 6 is a top plan view of the electronic device of FIG. 1; and,

FIG. 7 is a bottom plan view of the electronic device of FIG. 1.

The broken lines, including those depicting the four parallel bars shown on the front surface in FIGS. 1, 2, and 4-7, the two terminals and speaker grills shown on the rear surface in FIG. 3, and the five features depicted on the bottom surface in FIG. 6 (and also visible in FIGS. 2-5) are directed to unclaimed portions and form no part of the claimed design.
